(57) **CLAIM**

An ornamental design for a belt segment as shown and described.

DESCRIPTION

FIG. 1 is an upper perspective view of the instant inventively designed belt segment.

FIG. 2 is a lower perspective view of the belt segment.

FIG. 3 is a side view of the belt segment.

FIG. 4 is an opposite side view of the belt segment.

FIG. 5 is an end view of the belt segment; and, FIG. 6 is an opposite end view of the belt segment.

Structures within Drawing FIGS. 1-6 that are not parts of the claimed design, but are considered necessary to show the environment in which the design is associated, are represented in said Drawing Figures by broken lines. Such structures represented by broken lines constitute unclaimed subject matter, and such structures form no part of the claimed design.

1 Claim, 4 Drawing Sheets
